UNITED STATES PATENT OFFICE.

MARY I. TOWNSEND, OF SEATTLE, WASHINGTON, ASSIGNOR OF TWO-THIRDS TO WILLIAM B. VAN VALIN, OF LOS ANGELES, CALIFORNIA.

DESIGN FOR A TOY FIGURE.

Application filed August 11, 1922. Serial No. 3,351. Term of patent 7 years.

To all whom it may concern:

Be it known that I, MARY I. TOWNSEND, a citizen of the United States, residing at Seattle, in the county of King and State of Washington, have invented a new, original, and ornamental Design for Toy Figure, of which the following is a specification, reference being had to the accompanying drawings, forming part thereof, in which—

I claim:

The ornamental design for a toy figure, as shown.

MARY I. TOWNSEND.
